H. R. HAERR

CASE

Filed June 15, 1922

UNITED STATES PATENT OFFICE.

HAROLD R. HAERR, OF CINCINNATI, OHIO, ASSIGNOR TO THE GRUEN WATCH COMPANY, OF CINCINNATI, OHIO, A CORPORATION OF OHIO.

CASE.

Application filed June 15, 1922. Serial No. 568,476.

To all whom it may concern:

Be it known that I, HAROLD R. HAERR, a citizen of the United States of America, and a resident of Cincinnati, in the county of Hamilton and State of Ohio, have invented new and useful Improvements in a Case, of which the following is a specification.

An object of my invention is to provide a case wherein the various wrist bands used with wrist watches, may be retained.

Another object of my invention is to provide a simple and compact device for the purpose stated.

Another object of my invention is to provide a device for the purposes stated wherein the several bands may be readily replaced and from which they may be readily removed, and wherein the bands may be selectively retained.

These and other objects are attained by means described herein, and disclosed in the accompanying drawing, in which:

Fig. 1 is a perspective view of a case embodying my invention.

Fig. 2 is a perspective view of an inverted block forming a detail of my invention.

Fig. 3 is an enlarged sectional view on line 3—3 of Fig. 2.

Fig. 4 is a sectional view on line 4—4 of Fig. 2.

The container 5 may be of any form and comprises a lower section 6 and a lid 7 hingedly mounted upon one another and being provided with suitable locking means such as the snap 8. The block 9 is of a size and shape such that it may be readily inserted in and removed from the lower section or base. To facilitate the removal of the block, a pair of hooks 10 are mounted upon the block in any suitable manner, and extend upwardly from the block. A strap or belt 11 is carried by the hooks whereby a firm grip may be had in order to remove the block. The block is provided with suitable covering 12 preferably in the nature of velvet which will serve both to give a neat finish to the block and to serve as a cushion. The lower portion of the block is recessed and carries a number of ribs which extend longitudinally of the recess. A closure plate 14 is hingedly mounted at its one end upon one end of the block and is adapted to lie between the side rails 15 and 16 of the block, thereby serving to cooperate with the

ridges in forming individual ways or compartments extending longitudinally of the block. Each of the ways 17 is adapted to receive a band 18 such as is used to secure the wrist watch 19 upon the arm of a wearer. The bands 18 are removably secured to the wrist watch, but whereas this feature is not involved in this application, no explanation of the matter whereby they are so made, need be given herein. The block has a window or slot 20 formed adjacent its one end, the slot extending transversely of the ways 17. The slot 20 is preferably disposed at the end of the block remote from the hooks 10 and adjacent that end of the block which carries the closure plate 14. When a number of bands, such as 18, which are incidently of various colors and materials, are disposed within the ways 17 and the block is inserted in the base 6, a small portion of each band 18 may be observed thru the window 20, and if desired, the bands 18 may be withdrawn from the ways thru the window. The watch 19 is retained in position upon the block by slipping the band 18, mounted on the watch at the time, transversely about the block, the band lodging in the depressions 21 and 22 formed in the side rails 15 and 16, the band 18 being contracted in order to secure the watch upon the block. The closure plate 14 is provided with a loop 23 which may extend between the block and the base 6 and project above the block whereby the block may, in the first instance, be removed from the base. When the watch is mounted upon the block, the band 18 extends around both block and the closure plate 14, wherefore, when the block is withdrawn from the base, the closure plate will not fall and thereby permit dislodgment of the bands from the ways 17.

The upper face of the block may be dished as shown at 24 to receive the watch.

What I claim is:

1. In a device of the class described the combination of a container, a block adapted to be removably carried by the container, having longitudinally extending ways formed in its under surface, and a slot extending therethru transversely of the ways, and a plate hingedly mounted on the block adapted to form a closure for the ways.
2. In a device of the class described the

- combination of a container, a block adapted to be removably carried by the container, having longitudinally extending ways formed in its under surface, a slot extending therethru transversely of the ways, a plate hingedly mounted on the block adapted to form a closure for the ways, and means whereby the block may be withdrawn from the container.
- 10 3. In a device of the class described the combination of a container, a block adapted to be seated in the container, and having a slot extending transversely of itself, ribs extending downwardly from the under face of the block, whereby ways are formed in the under surface of the block, the ways terminating upon the slot in the block, a hinged plate adapted to engage the ribs and to form a closure for the ways, and means to removably retain the plate in engagement upon the ribs. 20
4. In a device of the class described the combination of a container, a block adapted to be seated in the container, and having a slot extending transversely of itself, ribs 25 extending downwardly from the under face of the block whereby ways are formed in the under surface of the block, the ways terminating upon the slot in the block, a hinged plate adapted to engage the ribs 30 and to form a closure for the ways, means to removably retain the plate in engagement upon the ribs, and means whereby the block may be withdrawn from the container. 35

In testimony whereof, I have hereunto subscribed my name this 13th day of June, 1922.

HAROLD R. HAERR.
